DESIGN FOR A COOKY JAR OR SIMILAR ARTICLE

Joseph Burgess Lenhart, Marietta, Ohio

Application June 19, 1944, Serial No. 114,089

Term of patent 14 years

(Cl. D58—25)

To all whom it may concern:

Be it known that I, Joseph Burgess Lenhart, a citizen of the United States of America, residing in Marietta, county of Washington, and State of Ohio, have invented a new, original, and ornamental Design for a Cooky Jar or Similar Article, of which the following is a specification, reference being had to the accompanying drawing, forming part thereof, wherein,

The characteristic feature of my design resides in the combination on the cooky jar or similar article disclosed, of the reversible face and body sections, as shown.

I claim:

The ornamental design for a cooky jar or similar article, substantially as shown, and described.

JOSEPH BURGESS LENHART.
